(57) **CLAIM**

The ornamental design for an eyeglass cleaning apparatus, as shown and described.

DESCRIPTION

FIG. 1 is a perspective view of the eyeglass cleaning apparatus in a closed configuration showing a brush in a retracted position;

FIG. 2 is a top view thereof;

FIG. 3 is a bottom view thereof;

FIG. 4 is a front view thereof;

FIG. 5 is a rear view thereof;

FIG. 6 is a left end view thereof;

FIG. 7 is a right end view thereof;

FIG. 8 is a perspective view of the eyeglass cleaning apparatus in a closed configuration showing a brush in an extended position;

FIG. 9 is a front view thereof;

FIG. 10 is a perspective view of the eyeglass cleaning apparatus in an open configuration showing a brush in an extended position;

FIG. 11 is a front view thereof; and,

FIG. 12 is a top view thereof.
